UNITED STATES PATENT OFFICE

GEORGE L. HOMMEL, OF IRONDEQUOIT, NEW YORK, ASSIGNOR TO BAUSCH & LOMB
OPTICAL COMPANY, OF ROCHESTER, NEW YORK, A CORPORATION OF NEW YORK

DESIGN FOR AN EYEGLASS AND SPECTACLE CASE

Application filed June 25, 1932. Serial No. 44,193. Term of patent 3½ years.

To all whom it may concern:

Be it known that I, GEORGE L. HOMMEL, a citizen of the United States, and a resident of the town of Irondequoit, county of Monroe, and State of New York, have invented a new, original, and ornamental Design for an Eye-glass and Spectacle Case, of which the following is a specification, reference being had to the accompanying drawing, forming a part hereof.

The figure shows a front elevation of an

eyeglass and spectacle case showing my new design.

The general shape of the spectacle case shown is conventional and the dominant feature of the design resides in the ornamental effect as shown.

I claim:

The ornamental design for an eyeglass and spectacle case substantially as shown and described.

GEORGE L. HOMMEL.
